[57] CLAIM

The ornamental design for a water craft, as shown and described.

DESCRIPTION

FIG. 1 is a top perspective view of a water craft showing my new design;

FIG. 2 is a bottom perspective view thereof;

FIG. 3 is a top plan view thereof;

FIG. 4 is a side elevational view thereof, the opposite side elevational view being a mirror image of that shown;

FIG. 5 is a bottom plan view thereof; and,

FIG. 6 is an end view thereof, with both end views of the water craft being identical.

FIG. 1

FIG. 2

FIG. 3

FIG. 4

FIG. 5

FIG. 6
